UNITED STATES PATENT OFFICE.

ERNEST O. FREDERICS, OF NEW YORK, N. Y., ASSIGNOR TO E. FREDERICS, INC., OF NEW YORK, N. Y., A CORPORATION OF NEW YORK.

FIXTURE.

Application filed August 23, 1926. Serial No. 130,873.

This invention relates to an improved fixture, and specifically, a fixture for use in connection with the permanent waving of hair and similar operations.

5 It is an object of the invention to provide a device of this character which, when utilized in connection with permanent hair-waving, may be employed with maximum facility and with a minimum discomfort to the 10 person being treated.

A further object of the invention is that of providing a fixture the parts of which will be compact, the heaters being movable to any required position and being maintained in this position throughout subsequent operations until the user desires to re-adjust the parts.

20 A still further object is that of providing a device of this character the parts of which will be simple in construction and relatively few in number, and which parts may be assembled to furnish a rugged machine capable of use over long periods of time with freedom from mechanical difficulty.

25 Other objects of the invention will in part be obvious and will in part appear herein-after.

The invention accordingly comprises the 30 features of construction, combination of elements and arrangement of parts which will be exemplified in the construction herein-after set forth, and the scope of the application of which will be indicated in the 35 claims.

35 For a fuller understanding of the nature and objects of the invention reference should be had to the following detailed description taken in connection with the accompanying drawings, in which:

40 Figure 1 is a side elevation of one form of fixture embodying the construction of the present invention; and

45 Fig. 2 is a similar, but somewhat diagrammatic, view thereof and showing the wiring of the apparatus.

50 Referring particularly to Fig. 1, the numeral 5 indicates the ceiling bell which may be provided in a device of this character, and from which a stem 6 extends downwardly, this stem supporting a crown plate 7, from which (in the present exemplification) upwardly-inclined arms 8 radiate, these arms mounting concentrically-disposed 55 supporting-rings 9.

The head of the machine is secured to the lower end of the stem, this head including a plate 10, preferably of a size similar to the plate 7, an outlet block 11 of preferably annular shape being mounted below the plate 60 10 and providing a series of outlet openings 12, pairs of which are adapted for selective reception of the prongs of plugs, hereinafter described. Extending between the plates 7 and 10, and preferably parallel to the stem 65 6, are rods 13, these rods slidably mounting counterweights 14, which, to this end, are provided with openings for the accommodation of these rods; these openings being of such size as to afford a firm sliding fit between these elements.

70 In the present instance, pairs of heaters 15 are coupled to common leads 16, and at the inner end of each of these leads a plug is secured, the latter providing a body 17 of insulating material and a pair of prongs 18 spaced a distance corresponding to the spacing of the openings 12.

75 Connecting members, for example, cords 18, have their outer ends attached to the 80 leads 16 at points preferably intermediate the plugs and heaters, and the inner ends of these connecting members are secured one to each of the weights 14, the bodies of the former passing over pulleys 19 associated 85 with the supporting-rings and the crown plate 7. Thus it will be understood that, due to the method of mounting the weights and the pull exerted by the heaters, the latter may be moved to any desired position by 90 the operator, and will maintain this position without a pull being transmitted through the connecting members and leads to the hair of the person being treated. At this time it will also be noted that the pairs of heaters 95 are arranged in two groups concentrically disposed with respect to each other, incident to the similar disposition of the rings 9 and the fact that the connecting members of adjacent pairs of heaters may pass over pulleys 19 associated with the innermost and outermost ring, respectively. Due to this arrangement of the parts, it will be obvious 100 that the heaters will not interfere with each other, although they extend in two concentric groups immediately adjacent each other.

105 As a consequence, the leads will extend substantially vertically from the head of the person being treated and will not extend at different acute angles, which has been a com- 110

mon cause of discomfort to the person operated upon.

Referring to Fig. 2, in which the wiring diagram has been shown schematically, the numeral 20 indicates the power leads, from which, in the present instance, the leads 21 and 22 extend; fuses 23 and switches 24 being interposed in these leads. It will be noted that the pair of leads 22 are connected 10 with one of the main leads and the lead 21 is connected with the other of the same. This latter lead is connected with a contact ring 25, to which socket members 26 are attached. The former leads are secured one to each of 15 semi-circular rings 27, these ring sections being insulated from each other, and socket members 28 being carried by each of the same. The socket members are disposed immediately to the rear of the outer face of 20 the plug block 11 and in line with the openings 12 thereof, and it is thus obvious that, upon the prongs 18 of the plug being introduced through a pair of the openings 12, these prongs will enter the socket members 25 26 and 28, and if the rings 25 and 27 are energized, current will flow through the heaters 15. In order that an operator may determine whether one or both sides of the 30 block 11 are energized, signal elements are provided, in the present instance embracing pilot lamps 29 positioned within sockets having one of their contact portions connected with the ring 25, their second contact portion being connected one with each of the ring 35 segments 27.

It is thus obvious that an operator may utilize one-half or all of the machine, and may become instantly cognizant of current failure. Due to the preferably concentrical 40 disposition of all of the parts, the grouping of the heaters is even and compact and they will directly overlie the head of the person being treated. Furthermore, the plugs may be removed and new heater units substituted, 45 if this becomes necessary, with a minimum of inconvenience to the operator; and finally, it will be appreciated that the entire apparatus may be shipped ready for use and installed with facility.

50 Thus, among others, the objects aforementioned have been accomplished; and since certain changes may be made in the above construction, and different embodiments of the invention could be made, without departing from the scope thereof, it is intended that all matter contained in the above description or shown in the accompanying drawings shall be interpreted as illustrative and not in a limiting sense.

55 It is also to be understood that the following claims are intended to cover all of the generic and specific features of the invention herein described and all statements of the scope of the invention herein described 60 and all statements of the scope of the inven-

tion which as a matter of language might be said to fall therebetween.

Having described my invention, what I claim as new and desire to secure by Letters Patent is:

70 1. A fixture, including a stem, spaced plates associated with said stem, rods extending between said plates, weights slidable upon said rods, an outlet block at the lower end of said stem, leads connecting current-consuming elements to said block, and means connecting said leads to said weights whereby the weights function as counterbalances.

80 2. A fixture, including a stem, a plate secured to said stem, radial and upwardly-extending arms having their inner ends secured to said plate, a plurality of concentrically-disposed rings secured to said arms, electrical leads associated with said stem, counterbalance weights disposed adjacent said stem, and flexible means connecting said weights with said electrical leads, certain of said flexible leads passing over points on one 85 of said concentric rings, and others thereof 90 passing over similar points on the other ring.

95 3. A fixture, including a stem, a plate secured to said stem, radial and upwardly-extending arms having their inner ends secured to said plate, a plurality of concentrically-disposed rings secured to said arms, electrical leads associated with said stem, counterbalance weights disposed adjacent said stem, and flexible connecting means attached to adjacent electrical leads passing alternately over non-friction supports on 100 said concentric rings.

105 4. A fixture, including a stem, an outlet block secured to said stem, current-consuming elements associated with said block, and means for energizing portions of said block and those consuming elements connected with such portions independently of the others.

110 5. A fixture, including a stem, an outlet block secured to said stem, current-consuming elements associated with said block, means for energizing portions of said block and those consuming elements connected with such portions independently of the others, and signalling means associated with each of the block portions for indicating when the portions are energized.

115 6. A fixture, including a stem, a substantially round outlet block secured at the lower end of said stem, a plate mounted by said stem, an annular series of rods extending between said plate and block, weights slidably mounted on said rods, electrical leads associated with said block, annularly-disposed suspending elements associated with said plate, said weights being connected to said electrical leads by flexible members 120 passing over said suspending elements.

7. A fixture, including a stem, an outlet block at the lower end of the same, a ring member within said block, a pair of semi-circular ring members also disposed within said block and spaced from each other and from said first ring member, a source of electrical current supply having one of its leads connected with said first-mentioned ring member, the other of its leads being 35 connected with both of said semi-circular ring members, current-consuming elements, connecting members extending between the same and said ring members, and means for disconnecting said source of current supply 40 from either of said semi-circular ring members, and signalling means associated with each of said semi-circular ring members for indicating when they are in closed circuit.
8. A fixture, including a stem, an outlet block secured to the lower end of said stem and having two series of openings, a contact member extending throughout the length of 20 one entire series, a second contact member comprising a plurality of portions extending to the rear of said second series of openings, a source of current supply connected with said contact members, and means for controlling the flow of current through said latter contact members.
9. A fixture, including a stem, an outlet block at the lower end of the same, a ring member within said block, a pair of semi-circular ring members also disposed within 30
- said block and spaced from each other and from said first ring member, a source of electrical current supply having one of its leads connected with said first-mentioned ring member, the other of its leads being 35 connected with both of said semi-circular ring members, current-consuming elements, connecting members extending between the same and said ring members, means for disconnecting said source of current supply 40 from either of said semi-circular ring members, and signalling means associated with each of said semi-circular ring members for indicating when they are in closed circuit.
10. A fixture, including a stem, an outlet 45 block secured to the lower end of said stem and having two series of openings, a contact member extending throughout the length of one entire series, a second contact member comprising a plurality of portions extending to the rear of said second series of openings, a source of current supply connected with said contact members, means for controlling the flow of current through said latter contact members, and signalling means associated with each of said latter contact members to indicate when they are in closed circuit.

In testimony whereof I affix my signature.

ERNEST O. FREDERICKS.
